KNITTING MACHINE

Samuel Mishcon, New York, Harry Agulnek, Brooklyn, and Lester Mishcon, New York, N. Y., assignors to Supreme Knitting Machine Co., Inc., Brooklyn, N. Y., a corporation of New York

Application June 26, 1948, Serial No. 35,376

19 Claims. (Cl. 66—138)

1

This invention relates to striping apparatus for knitting machines—and in its broader aspect, to an internal camming mechanism disposed on a rotatable machine member and movable radially on said member through the action of a separate and remote control.

The application of our invention for producing various colored stripes on knitted material is intended, in accordance with one of our objectives, to eliminate in circular knitting machines the conventional rotating yarn stand, whereby the rotating member will be the cylinder with a revolving take-up, and the machine provided with a multiple arrangement of stationary striping boxes actuated in a novel manner, as will hereinafter appear. Our invention eliminates the known disadvantages inherent in rotating yarn stands, the relatively high peripheral speeds of which produce uneven feeding, particularly due to the air friction effects upon certain new types of fine yarns now commonly used.

It is within the contemplation of our invention, with respect to the last-mentioned aspect thereof, to employ a plurality of four-finger striping boxes, and to provide means whereby they are actuated by a silent and relatively slow-moving cam which is entirely concealed from view. And in the furtherance of this object, it is also within our contemplation to enable colors to be selectively knitted by a machine arrangement consisting of a minimum of mechanical parts, with a minimum of operative movements to eliminate undesirable centrifugal effects during the rotation of the cylinder.

It is a further object of our invention to enable the color selecting mechanism to be employed without interfering with the conventional feeds on the machine.

Another object is to enable the color selection to be readily made by conveniently located control mechanisms disposed at the outer periphery of the machine, without the necessity of making any control adjustments within the interior of the machine.

Among the most important objectives of our invention is the provision of a type of loosely mounted cam actuated through remotely disposed automatic selective controls, without the employment of linkage or other continuous connections or complicated electrical mechanisms for effectuating the controlled movement of the cam. In a preferred form of our invention, and in the accomplishment of the said objective, we provide a slide cam disposed upon the rotary cylinder mounting, and movable radially under the actua-

2

tion of said control mechanism, such radial motion producing predetermined operative movements of the striping or other fabric design members—the said slideable cam having one radial path of movement, and not being connected to the machine by fastenings, so that it can readily be removed and replaced.

And it is a further object to provide a relatively simple and readily constructed device capable of performing the functions and having the advantages aforementioned.

Other objects, features and advantages will appear from the drawings and the description hereinafter given.

15 Referring to the drawings:

Figure 1 is a plan view, with fragments broken away for clarity, of a circular knitting machine embodying our invention, the drawing showing a plurality of striping boxes and the automatic striping control mechanism disposed at the outer periphery of the machine.

Figure 2 is a fragmentary elevation of the striping control mechanism shown somewhat enlarged, viewed from line 2—2 of Fig. 1.

20 Figure 3 is a sectional view taken substantially along lines 3—3 of Fig. 1 and lines 3—3 of Fig. 2.

Figure 4 is a sectional view of Fig. 2 taken substantially along line 4—4 thereof.

25 Figure 5 is a fragmentary plan view, partially in section, of the cylinder gear ring and outer housing ring, showing the cylinder ring cam for actuating the chain control mechanism, also shown in Figs. 3 and 4.

Figure 6 is a fragmentary plan view, with parts broken away for clarity, showing the main T-cam of our invention in its outer or operative position, and about to be returned by the stationary return pin extending downwardly from the cam retainer ring.

30 Figure 7 is a view substantially like Fig. 6, but showing the cam in its retracted position, just prior to engaging the movable operative pin, for radial movement towards its outer operative position.

35 Figure 8 is a view substantially like Fig. 7, showing the cam in its outer operative position, substantially like that shown in Fig. 6, but with the movable operative pin disposed within the channel of the cam.

Figure 9 is a perspective view of the T-cam above-mentioned.

Figure 10 is a fragmentary section of Fig. 8 taken substantially along line 10—10 thereof.

50 Figure 11 is a rear or outer perspective view

of the knitting machine, showing the striping boxes and actuating mechanism thereof.

Figure 12 is an enlarged side elevation, partly in section, of the ratchet mechanism for operating the drum striping feed clearly shown in Fig. 11.

Figure 13 is a front or inner perspective view of the knitting machine, showing the striping boxes and cutting means in operative position.

Figure 14 is a front view, looking outwardly from within the cylinder, of one of the striping boxes, with the gear cover removed and showing the gears in section.

Figure 15 is a section of Fig. 14 taken substantially along line 15—15, and

Figure 16 is a schematic section taken along a vertical plane through the machine of Fig. 1, showing the relative positions of the striping fingers in their operative and inoperative positions, and the positions of the yarns therefrom with respect to the center post and the knives of the device.

In the particular embodiment of our invention illustrated in the figures, there is shown a circular knitting machine having a stationary outer housing ring 28, a stationary cam retainer ring 21, and a revolving cylinder and gear ring 22 containing a circular gear 23 driven by a mechanism not shown, but well known in the art. The revolving cylinder 24 contains circumferentially disposed thereabout a plurality of independent latch needles 25 of conventional construction, as well as a plurality of sinker elements 26 cooperative therewith (Fig. 16), said sinkers not herein otherwise shown, since they are well known in the art, further description not being required for the purpose of this specification.

Circumferentially disposed about the apparatus are a plurality of stationary striping boxes 27, each containing four fingers or yarn carriers 28, 29, 30 and 31, said fingers being of conventional construction and containing apertures through which extend yarns 32, 33, 34 and 35 from cones disposed on a stationary yarn stand thereabove supported by the posts 36, 37 and 38 (Fig. 1)—the yarn stand and cones not being herein illustrated inasmuch as it is of conventional construction well known in the art, and since a detailed description thereof is not necessary for the understanding of the present invention. Disposed below each set of striping fingers is a needle latch guard 39 (Figs. 15 and 16) containing a yarn ledge 40, the wall 41 of the guard being engageable with the latch 42 of the needles 25 in conventional manner.

The striping fingers are pivotally mounted and are movable between an upper inoperative position and a lower operative position. In the illustrations, particularly in Figs. 13 and 16, finger 30 is shown in an upper inoperative position, and finger 29 in a lower operative position. When a selected finger is in its lower operative position, the yarn 33 carried thereby is disposed over and rests upon the ledge 40 and is in operative engagement with the needle 25 whereby it is incorporated into fabric 43 in conventional manner (Fig. 16). The yarn 34 from the inoperative or raised finger 30, not being engaged by a needle, is carried around by the rotating cylinder until it ultimately engages the central post 44, and as the cylinder continues to rotate the yarn is wrapped around the said central post until it reaches the knife 45 mounted on bracket 46 attached to central post 44—the level of the portion 34a of yarn 34 being lower on its return, so that it will intercept the cutting edge of knife

45. If the tension in the yarn is insufficient to produce a cutting thereof, the yarn will simply slide over the inclined cutting edge of the blade, and continue to revolve until it wraps itself around in another convolution about post 44, whereupon it will be prevented from slipping about said post and will be relatively taut when it reaches the diametrically opposite knife 47, to be cut thereby. The cutting action here described is a conventional step, and is herein referred to only to aid in the general understanding of the invention.

From the above it is apparent that the movement of the striping fingers from their inoperative to their operative positions will determine when striping yarns are incorporated in the fabric. Since the fingers may carry differently colored yarn, various fabric colors or striping effects can obviously be obtained by selectively actuating one of the striping fingers on each of the striping boxes, or by permitting all of the striping fingers to remain inoperative during a revolution of the cylinder. An essential part of this invention concerns itself with a striping control mechanism capable of actuating a selected striping finger on each of the striping boxes during a revolution of the cylinder.

Each striping box contains a rotating drum 48 disposed within casing 49 (Figs. 14 and 15) and mounted upon shaft 50 upon which is affixed gear 51 in engagement with gear 52 mounted upon shaft 53 upon which is affixed the ratchet wheel 54a. Each drum contains a plurality of holes 54, preferably threaded, into which are inserted plugs 55, the outer terminals of the plugs extending beyond the outer surface of drum 48. The said holes 54 are arranged in four circumferential rows, each disposed under and in line with the rear arm 56 of a striping finger. As will be seen from the drawings, the holes on the adjacent circumferential rows are in horizontal alignment (Fig. 11). In setting these plugs, as will more clearly hereinafter appear, there is only one for each horizontal row, so that only one of the fingers will be actuated at a time for each striping box.

The said shaft 50 extends through the casing 49, one terminal of which has mounted thereover the outer index drum 57 containing numbers thereon corresponding with each of the horizontal rows on the inner drum, to help in setting the device.

Each of the striping fingers is pivotally mounted at 58 within its striping box, the undersurface 59 of the rear arms 56 being adapted for slidable engagement with the tops of said studs 55. Each finger has associated therewith a spring 60 normally urging the finger upwardly into its inoperative position, in obvious manner. Thus, when the rear arm 56 of a finger is not in engagement with a stud 55, it will rest upon the lateral surface of the drum 48, as in the case of finger 30 (Fig. 15), the spring 60 exerting a yieldable pressure thereagainst. However, when the drum 48 moves in the direction of the arrow A (Fig. 15), an underlying stud 54a will cause an elevation of the arm 56 of the finger and a consequent depression of the forward part of the finger, whereby the finger is brought into its operative position, as indicated by finger 29.

Adjacent each striping box is a pawl 61 in engagement with the teeth on the cooperating ratchet wheel 54a. By the mechanism of our invention, to be further hereinafter described,

each of said pawls is raised in accordance with a selective setting of the control mechanism, causing an operative rotation of the ratchet wheel for each such actuation of the pawl 61. According to our invention, there are as many teeth on the ratchet wheel as there are horizontal rows of holes on the drum 48, so that each operative movement of the pawls 61 causes a positioning of a row of holes on the drum 48 below the rear arms 56 of the fingers. The arrangement is hence such that successive actuations of pawls 61 will cause successive movements of horizontal rows of holes into operative positions underlying the said rear arms 56 of the fingers. And since there is a plug disposed within one of the holes below one of said arms 56, it is apparent that the corresponding striping finger will be brought into its depressed or operative position, as illustrated by the finger 29 in Figs. 15 and 16. The manner in which pawls 61 are actuated will now be described.

Pawl 61, at each striping feed, is pivotally mounted at 62 within the bifurcated support 63, the rod 64 being secured, by pin 65, to the lower bifurcated portion of said support 63, said rod extending downwardly and being in slidable engagement with the central aperture 66 of the vertical guide member or guide 67. An enlarged intermediate portion 68 of rod 64 is in slidable engagement with the inner wall 69 of the enlarged central chamber 70 within guide 67—the lower terminal 71 of rod 64 being preferably rounded and engageable either with the flat horizontal floor 72 of the rotating cylinder ring 22, or with the upper cam surface 73 of the cam 74, to be hereinafter described. The two operative positions of the lower terminal 71 is indicated by full and dot-dash lines in Fig. 12. A spring 75, disposed within central chamber 70 of the guide 67, normally urges rod 64 downwardly, so that its said terminal 71 is in yieldable pressing engagement either with said floor 72 or said cam 74. The guide member 67 is held against displacement by fasteners 76a securing the flange 76 to the cam retainer ring 21.

The said cam 74 is slidably movable reciprocatingly and radially in the directions of arrows B (Fig. 12). When it is in its innermost or inoperative position (to the right), the said terminal 71 of rod 64 is in engagement with floor 72, in a manner to be hereinafter described. And when the said cam 74 is in its outermost operative position (to the left), the said terminal 71 is brought to its raised position indicated by full lines in Fig. 12—the said upward movement being against the action of spring 75 and producing a corresponding upward movement of pawl 61, and a corresponding clockwise rotation of the ratchet wheel 54a. When the said cam 74 is again retracted (to the right), the spring 75 will urge the rod 64 downwardly, bringing the terminal 71 into engagement with the cylinder ring floor 72, and also bringing member 63 and 67 into abutting engagement, as clearly shown in Fig. 11. The spring 71, disposed within a recess in support 63, is in engagement with the bottom extremity 78 of pawl 61 at a point rearwardly of pivot 62—thereby permitting a slidable retraction of the pawl 61 when its operative tip is caused to slide down along the underlying tooth, upon an operative lowering of rod 64.

It is thus apparent that each drum actuator, embodied in pawl 61, rod 64 and associated parts, is operated only when the cam 74 has been moved to its outer or operative position (to the left).

When cam 74 remains in its retracted position (to the right), the drum 48 remains stationary, and no change whatsoever takes place in the striping action of the striping feed.

The above mentioned cam 74 is one of the main elements of our invention, its construction being clearly disclosed in Fig. 9. This device is substantially T-shaped in appearance, and contains a pawl-actuating cam surface 73 disposed at the top of the narrow arcuate cam strip 79, the upper cam surface along strip 79 containing a thin leading edge 80 gradually increasing in thickness to uppermost portion 81, and thereafter being gradually reduced in thickness to the rear or trailing edge 82. The vertical distance between the lowermost surface 83 of strip 79 and the uppermost surface 81 thereof represents the total effective operative rise of the cam—which is equivalent to the total operative rise of pawl 61. The outer surface 84 of strip 79 is convexly curved in the shape of an arc to fit the arcuate contour of the inner wall 85 of the rotating gear ring 22 (Figs. 6 and 8). The cam 74 further contains integral therewith the substantially radially extending block 86 disposed intermediate the leading and trailing edges 80 and 82 and joining the inner portion 87 of the strip 79. Said block portion 86 is proportioned to slidably fit within the recessed portion 88 of the rotating cylinder ring 22, said recessed portion 88 being radially disposed so as to permit a radial slidable movement of the cam 74, as will more clearly hereinafter appear. The said block 86 contains on its upper surface a substantially V-shaped recess 89 having oppositely disposed vertical cam walls 90 and 91. The said cam walls converge inwardly from their respective leading edges 82 and 83 towards a notched opening 92.

The entire cam 74 is placed upon the rotatable cylinder ring 22 so that the extension block 86 is, as aforesaid, disposed within the said recess 88, the elongated arcuate strip portion 79 being disposed outwardly therefrom. In the position of the cam 7 shown in Fig. 6, it is in its outer operative position. As the cylinder ring 22 rotates in the direction of the arrow, the vertical cam wall 91 will encounter the downwardly extending stationary retracting pin 95, said pin being affixed to the plate 21. Since the said cam 74 moves with the ring 22, the pin 95, when coming into engagement with cam surface 91, will cause the entire cam 74 to move to the right radially until it reaches its inoperative position shown in Fig. 7. It should be noted, by referring to Fig. 7 that the pin 95 is shown immediately behind the notch 94, the said notch portion being of a width sufficient to clear the pin 95 upon the circumferential movement of cam 74 with the cylinder.

It will be noted, in Fig. 7, that there is another pin 96 (see also Fig. 10), which is in the path of outer vertical cam surface 90. The arrangement is hence such that when the said pin 96 is in such obstructing position, it will engage surface 90 and slidably actuate the cam 74 radially outwardly until the cam is in the operative position shown in Fig. 8 (also in Figs. 6 and 12). When cam 74 reaches its said operative position, the said actuating pin 96 is disposed within said opening 94, being disengaged from block 86 as the rotary motion continues, so that the cam 74 is permitted to continue along its path without obstruction.

The said actuating pin 96 is movable from its lowered operative position, shown in full lines in Fig. 10, to a raised inoperative position, shown by dot-dash lines, whereby the lower terminal of the

pin is retracted to a position where it is out of engagement with cam wall 90—that is, in a position where it is above the upper surface of block 86. The operative movements of pin 96 are controlled by a mechanism to be now described.

A bracket 97 contains two oppositely disposed arms from which depend the said pin 96 and the guide pin 98 slidably movable within aperture 99 of plate 21, pin 96 being slidably movable within aperture 100 of plate 21. The said bracket 97 is pivotally articulated with the lever arm 101 (Figs. 1, 4, 7 and 10), the pivotal connection being the pin 102. The opposite end of arm 101 contains the hollow boss 103, which is keyed on to one terminal of shaft 104, the opposite terminal carrying the arm 105. Mounted over shaft 104 is the helical spring 106 normally maintaining the lever 101 in its raised position, whereby the said actuating pin 96 is normally disposed in its inoperative position. In abutment with arm 105 is the stud 107 (Figs. 4 and 6), said stud being carried by the bracket 108 affixed to the inner terminal 109 of the plunger 110 which is slidably mounted within the support 111—the forward tip 112 of the plunger protruding from said support 111. The said stud 107 is adjustably positioned within bracket 108, in accordance with a predetermined setting.

Rotatably mounted adjacent the tip 112 of the plunger 110 is the timing chain 113, said chain being mounted upon the sprocket wheel 114 keyed to shaft 115, said shaft being supported by bearing 116 (Fig. 2), the outer terminal of the shaft having affixed thereto the hand wheel 117. The chain 113 contains two types of links, the low links 118 and the high links 119. The arrangement is hence such that upon an operative rotation of chain 113, only the high links 119, upon engagement with the tip 112 of plunger 110, will cause the plunger to move inwardly. Such inward movement of the plunger will carry the bracket 108 inwardly, thereby bringing the stud 107 into abutting engagement with the arm 105. This actuates the shaft 104 against the action of spring 106, whereupon the arm 101 will be depressed, and the actuating pin 96 brought into its operative position.

The said chain 113 is rotatably actuated intermittently through a distance of one link for each revolution of the cylinder. This is accomplished by the reciprocating action of the pawl 120 the tip of which is engageable with the teeth of the ratchet wheel 114a, as shown in Figs. 3 and 4. The said pawl is pivotally carried by the outer bifurcated terminal 121 of the follower arm 122, the pin 123 serving as the pivotal connection. The inner terminal arm 122 contains the follower roller 124 which is in rolling engagement with the lateral cam surface 125 of the rotating cylinder ring 22. The said cam surface 125 is formed by recessing said ring 22 inwardly, the depth of such recess being equal to the predetermined stroke of pawl 120. In abutting engagement with the extension of pin 123 is the spring 126 contained within the recessed portion of bracket 126 mounted upon the outer housing ring 20.

It is thus apparent that in order to set the apparatus above described to obtain striping effects on the fabric being knitted, the plugs 55 on the striping box drum 48 must be inserted in such holes as to actuate selected fingers carrying the colored yarn. When this has been accomplished, for each striping box, the sequence of finger actuation of each striping box will have

been set—so that predetermined color or striping effects can be obtained every time a finger is actuated. This actuation occurs every time that the cam 74 is in its outer or operative position. To move said cam 74 into its operative position, a timing chain 113 with a predetermined arrangement of high and low links is selected, whereby only at certain times will the plunger 110 be actuated to depress the actuating pin 96 and cause an outward movement of cam 74, for producing successive operative liftings of pawls 31 as the cam 74 passes each striping box feed.

It will be observed that the two actions of moving the cam 74 into its inoperative position and then into an operative position occur at close intervals, since the pins 95 and 96 are closely spaced along the circumference of the machine, the circumferential distance between the two pins being less than that between two adjacent striping boxes. The arrangement is such as not to interfere with any striping or knitting action of the machine whatsoever.

It will further be noted that the entire operative movement of the cam 74 relative to the cylinder ring 22 is reciprocating and radial, and that such movement is along a relatively short path. The operation is thus obviously simple, and has been found to be conveniently quiet. Cam 74 is entirely concealed, and is a completely independent unit, not fastened to any member of the apparatus, and can readily be removed from the cylinder ring when the cover 21 is removed. Despite the fact that there are no links or fasteners connecting the cam 74 with the selective control mechanisms, it is nevertheless apparent that selective striping operations can be readily effectuated. The setting of the apparatus can be done at the striping box drums and at the timing link-chain control, without any need to make adjustments or settings within interior portions of the machine, and without the necessity of connecting or disconnecting the said cam 74.

The arrangement is also such that there is no interference whatsoever with the other knitting elements of the machine, such as the pattern wheels 127.

In the above description, the invention has been disclosed merely by way of example and in preferred manner; but obviously many variations and modifications may be made therein which will still be comprised within its spirit. It is to be understood, therefore, that the invention is not limited to any specific form or manner of practicing same, except insofar as such limitations are specified in the appended claims.

We claim:

1. In a circular knitting machine for the production of striped fabrics, a revolving cylinder ring carrying a needle cylinder, a plurality of stationary striping boxes circumferentially disposed about the machine, each striping box having a plurality of yarn carrying fingers movable between predetermined operative and inoperative positions and a rotatable drum for selectively operating said fingers, a movable actuator operatively connected to each drum for rotatably actuating it, a cam slidably mounted on said cylinder ring and movable relatively thereto between a retracted and an operative position, said cam when in its operative position being adapted to successively engage said actuators and operatively move them as the cylinder ring revolves, whereby the said striping box drums will be successively rotatably actuated.

2. In a circular knitting machine for the production of striped fabrics, the combination according to claim 1, further provided with a ratchet wheel operatively connected to each of said drums, the said actuators each including a pawl and a substantially vertically disposed rod yieldably urged towards said cylinder ring.

3. In a circular knitting machine for the production of striped fabrics, the combination according to claim 2, the bottom terminals of each of said actuator rods being in slidable engagement with the floor of the cylinder ring when the said cam is in its said retracted position.

4. In a circular knitting machine for the production of striped fabrics, the combination according to claim 3, the said cam having an upper surface with which said rod terminals are in slidable engagement when the cam is in its said operative position, the rise of the cam being equal to the predetermined operative movement of the said actuator.

5. In a circular knitting machine for the production of striped fabrics, the combination according to claim 4, the said cam having an elongated strip containing said upper cam surface, said strip having relatively thin leading and trailing edges with rising cam surfaces converging therefrom to a high-level surface constituting the highest level of the cam.

6. In a circular knitting machine for the production of striped fabrics, the combination according to claim 1, said cam being movable radially, relative to the cylinder ring, between inner and outer limiting positions.

7. In a circular knitting machine for the production of striped fabrics, the combination according to claim 6, said inner limiting position being the retracted position of the cam, and said outer limiting position being the operative drum-actuating position of the cam.

8. In a circular knitting machine for the production of striped fabrics, the combination according to claim 1, the cylinder ring being provided with a recessed portion for slidably accommodating the cam.

9. In a circular knitting machine for the production of striped fabrics, the combination according to claim 8, said recessed portion having substantially radial walls, to limit the operative sliding movement of the cam to a substantially radial path.

10. In a circular knitting machine for the production of striped fabrics, the combination according to claim 1, the said cam being substantially T-shaped and comprising an elongated strip with an upper cam surface for engaging said actuators and a block extending substantially radially therefrom, the said cylinder ring being provided with a substantially T-shaped recessed portion for slidably accommodating the cam.

11. In a circular knitting machine for the production of striped fabrics, the combination according to claim 1, said cam having two oppositely disposed, vertical, converging cam walls, further provided with two pins adapted for engagement with said converging walls, one to slidably move the cam to its said retracted position and the other to slidably move it to its said operative position.

12. In a circular knitting machine for the production of striped fabrics, the combination according to claim 11, the said vertical cam walls converging from their leading to their trailing edges, said trailing edges being separated to form

a notched opening, said opening being proportioned to clear said pins.

13. In a circular knitting machine for the production of striped fabrics, the combination according to claim 12, the said cam retracting pin being disposed radially inwardly relative to the other pin and being in the path of the notched opening when the cam is in its fully retracted position, the other pin being in the path of the notched opening when the cam is in its operative position.

14. In a circular knitting machine for the production of striped fabrics, the combination according to claim 1, said cam having two oppositely disposed, vertical, converging cam walls, further provided with two pins adapted for engagement with said converging walls, one to slidably move the cam to its said retracted position and the other to slidably move it to its said operative position, the cam retracting pin being disposed in advance of the other pin, whereby the retracting pin will operatively engage the cam before it is engaged by the other pin.

15. In a circular knitting machine for the production of striped fabrics, the combination according to claim 14, the circumferential distance between the two pins being less than that between two successive striping boxes.

16. In a circular knitting machine for the production of striped fabrics, the combination according to claim 1, said cam having two oppositely disposed, vertical, converging cam walls, further provided with a fixed pin and a retractable pin adapted for successive engagement with said converging walls, the fixed pin to slidably move the cam to its said retracted position and the retractable pin to slidably move it to its said operative position.

17. In a circular knitting machine for the production of striped fabrics, a stationary outer housing ring, a revolving cylinder ring carrying a needle cylinder, a plurality of stationary striping boxes circumferentially disposed about the machine, each striping box having a plurality of

45 yarn carrying fingers movable between predetermined operative and inoperative positions and a rotatable drum for selectively operating said fingers, a movable actuator operatively connected to each drum for rotatably actuating it, a cam

50 slidably mounted on said cylinder ring and movable relatively thereto between a retracted and an operative position, said cam when in its operative position being adapted to successively engage said actuators and operatively move them as the cylinder ring revolves, whereby the said striping box drums will be successively rotatably actuated, said cam having two oppositely disposed, vertical, converging cam walls, a fixed pin and a retractable pin adapted for successive engagement with

60 said converging walls, the fixed pin to slidably move the cam to its said retracted position and the retractable pin to slidably move it to its said operative position, a timing chain rotatably mounted on the said stationary housing and

65 operatively connected to the said retractable pin, a ratchet wheel connected to the timing chain, a pawl engageable with the ratchet wheel, a follower operatively associated with the pawl, and a cam surface on the lateral wall of the cylinder ring with which said follower is in yieldable engagement, whereby an operative movement of the follower will cause an operative actuation of the retractable pin.

18. A camming mechanism comprising a re-75 volvable member, a substantially flat horizontal

floor revolvable with the member, a cam slidably mounted on said floor and movable relative thereto between two limiting positions, said positions being at different distances from the center of rotation measured along a horizontal plane, an element adapted to be actuated by said cam and operatively engaged thereby when the cam is in one of said limiting positions, and a cam control intermittently engageable with the cam for operatively moving it between said limiting positions, said cam control being operatively associated with the said revolvable member, said cam being out of engagement with said cam control except when operatively actuated thereby.

19. A camming mechanism according to claim 18, the slidable movement of the cam being in a generally radial direction transverse to the direction of rotation of the revolvable member.
